COMBINED WRAPPING TABLE AND DISPENSER UNIT

Richard R. Perdue, Taylors, S.C.

Application March 12, 1959, Serial No. 54,961

Term of patent 14 years

(Cl. D55—1)

FIG. 1.

FIG. 2.

The roll of film or paper shown in broken lines is for purpose of illustration.

The characteristic feature of my design for the combined wrapping table and dispenser unit disclosed resides in the upstanding dispenser unit having the configuration shown.

I claim:

The ornamental design for a combined wrapping table and dispenser unit, substantially as shown and described.
